MEANS FOR SMOOTHING THE LININGS
OF SHOES

John Hoza, Eelcamp, Md.

Application April 1, 1940, Serial No. 327,277
In Czechoslovakia May 2, 1938

4 Claims. (Cl. 12—51)

In the manufacture of shoes it is often necessary to smooth the lining of the upper, that is, so to level and even it that in the interior of the finished shoe there are no bulges or creases of the lining which would be liable to irritate the foot.

Such bulges and creases of the lining are removed in the finishing of the shoe by a smoothing operation, and there are already known different methods and devices for effecting this operation.

For example, smoothing has been effected by hand, by ironing out bulges or the like by means of a heated iron. Or the smoothing operation has been effected mechanically, but in this latter case the material was smoothed only around the top without the interior being ironed out. These known methods are open to the objection that the required function was not adequately fulfilled, and result in shoes with incompletely ironed linings, that is, the inner lining, save at the edge around the opening, remained unironed and had in some cases to be subsequently ironed by hand. The smoothing operation was effected on that piece which formed a stand for the shoe and the same stand was used for all kinds of shoes. The use of a common stand is open to the objection that it was not possible to iron out completely the interior of the shoe.

The invention provides a method of and a device for smoothing the linings of shoes which obviates the drawbacks of known constructions and effects smoothing of the entire interior of the shoe from the heel to the waist at the same time as the welt, there being used for treating each shoe three jaws and a last member, preferably a last without a toe portion, the last members being shaped to the inner form of the shoes.

A system of such last members is arranged on a rotatable ring in suitable number, the last members being individually exchangeable, so that it is possible to exchange the smoothing devices, depending on the nature of the shoes to be treated.

An embodiment of the smoothing device according to the invention is illustrated in the accompanying drawings.

In the drawings:

Fig. 1 illustrates a front elevation view of the device, with parts in section, and

Fig. 2 illustrates a vertical sectional view of the device taken through the axis of rotation of the disc carrying the last members.

On the horizontal shaft 2 there is rotatably arranged a disc 1 with last members 3 mounted

on the periphery. These members 3 are removably mounted to permit exchange, depending on the style and size of the shoes to be treated. Their number may be as desired and is preferably even for right and left hand feet. Associated with each member 3, are two side jaws 4 and a heel-engaging jaw 5. The jaws 4 are mounted on arms 6 and the jaws 5 are mounted on arms 7. The arms 6 and 7 are mounted on the eccentric studs 8, 9, adjustment of the pressure during the smoothing operation being permitted by the eccentric mounting of the studs 8, 9. The studs 8 are mounted on the disc 1; the studs 9 are likewise mounted on the disc 1 but to the rear.

The inner ends of the arms 6 and 7 are provided with track faces on which travel rollers 10 mounted on the lever system 11, 12 influenced by the springs 13. The springs 13 neutralise irregularities which might have influence on the operation of the machine, that is, in the case where heavy resistance may be met with in the smoothing operation the pressure is diminished by the action of the springs 13.

The actuation of the jaws 4 and 5 of the several smoothing systems is effected by a driving motor from which power is transmitted by way of a belt 19 to a layshaft 18 which actuates a semi-rotation clutch. By the operation of the hand lever 17 the clutch is caused to drive the shaft 16 on which are provided two eccentrics 15 which are angularly displaced to the extent of 180°. By virtue of the relative position of the eccentrics, there is effected alternate clamping of the jaws 4 and 5 for a left foot and a right foot. On the engagement of the clutch, the appropriate eccentric 15 is engaged by rollers 14 mounted on the levers 11, 12. Thereby the levers 11, 12 and therewith the rollers 10 are shifted in the direction towards the track faces of the arms 6, 7 and effect the closure of the jaws 4 and 5.

The last members 3 are heated by electric current which is led from the slip rings 21 by way of a cable to heating elements 22 provided for the several last members. The temperature of the last members 3 can be adjusted and maintained at the required degree by provision of a regulator such as the thermostat 23. The thermostat is influenced by an independent last member 24 which answers to the average dimensions of the last members 3 arranged on the disc 1.

The last members 3 are constructed in a form which corresponds to lasts for the type of shoe to be smoothed. They are in the nature of in-

complete lasts without toe portions to permit easy fitting.

Likewise the jaws 4 and 5 are constructed according to the exact form of the surface of the shoe to be smoothed. They are faced with resilient material 25 to permit adaptation to small differences in the shoes to be smoothed. Also the jaws have a facing 26 of softer elastic material than the base material 25. This facing is provided at the point of curvature of the shoe where the lining is most compressed. This facing 26, which projects from the plane of the elastic material 25, exercises on compression of the jaws 4 a greater pressure at the waist and thereby improves the smoothing operation.

Also the jaw 5 is likewise completed by elastic material 27 corresponding to the shape of the surface of the heel. The facings 26 and 27 are coated with leather, for example. This jaw 5 is so arranged that it also smooths the heel portion which heretofore had to be smoothed by hand.

By means of the jaws 4 and 5 so constructed, the lining of the shoe is smoothed at the heel and at the curved portions, the welts being also smoothed at the same time. There is thus realised an improvement of the external appearance of the shoe as well as perfect smoothing of the lining.

If desired, it is possible so to shape the jaws 4 that they smooth only the left side or the right side of the shoe as may be necessary in the manufacture of orthopaedic shoes.

Normally, smoothing is effected on one pair of last members suitable for the style and size of the shoes. For smoothing the linings of shoes of other sizes, the disc 1 is rotated until the required size of last member 3 is brought opposite the levers 11, 12. The disc 1 is adapted to be released and secured in position by operation of the treadle lever 20.

It is also possible to smooth only the left shoe or the right shoe and to cut out the second smoothing system. This result is obtained by shifting the eccentrics 15 axially of the shaft 16 by means of the lever 28, whereby the right or the left last member is cut out of operation.

The mode of operation is as follows:

According to the style of the shoe to be treated there is located opposite the operative the appropriate pair of last members 3 with smoothing systems 4 and 5, so that it is possible to smooth the right shoe and the left shoe. The electric current is switched on whereby the last members 3 are heated to the temperature set by the thermostat 23. On attainment of the desired temperature of the last members 3 the smoothing operation is commenced. Depending on whether only the left shoe or only the right shoe or both shoes are to be smoothed successively, the levers 11, 12 are brought by the lever 28 either into engagement or out of engagement with the eccentrics 15. Now the operator sets the shoe on one of the last members 3 and by means of the lever 17 brings the clutch into engagement whereby to effect rotation of the shaft 16 with the eccentrics 15. When the smoothing operation for the last member fitted with the shoe is completed, the jaws associated with said last member are opened and the second shoe of the pair placed on the appropriate last member 3. The clutch is again engaged by operation of the lever 17 and the

shaft 16 with the eccentric 15 brings the second shoe into the closing position of the smoothing device and so on.

The maintenance of the temperature at the required degree is effected by the thermostat 23 as aforesaid. In case the temperature should rise beyond the permitted extent, the thermostat cuts off the supply of current to the heater 22. When the temperature drops, the thermostat closes the circuit through the heater 22 so that the temperature of the last members 3 is maintained at the required level.

The smoothing operation is effected rapidly, regularly and thoroughly.

I claim:

1. A device for smoothing the linings of shoes comprising a disc rotatable about a horizontal axis, last members exchangeably mounted on the periphery of said disc, heating elements within said last members, connections for the supply of current to said heating elements, clamping jaws engageable with both sides and the heel respectively, of shoes mounted on said last members, a motor driven drive shaft, and means operated by said drive shaft and operatively engaging the clamping jaws associated with any selected pair of last members for moving said jaws into and out of engagement with the shoes on said last members.

2. A device for smoothing the linings of shoes comprising a disc rotatable about a horizontal axis, last members exchangeably mounted on the periphery of said disc, heating elements within said last members, connections for the supply of current to said heating elements, clamping jaws engageable with both sides and the heel respectively, of shoes mounted on said last members, a rotatable shaft provided with two eccentrics, and pivotally mounted levers actuated by said eccentrics for moving said clamping jaws into and out of operative engagement with the shoes on said last members.

3. A device for smoothing the linings of shoes comprising a disc rotatable about a horizontal axis, last members exchangeably mounted on the periphery of said disc, heating element within said last members, connections for the supply of current to said heating element, clamping jaws engageable with both sides and the heel respectively, of shoes mounted on said last members, a rotatable shaft provided with two eccentrics, pivotally mounted levers actuated by said eccentrics for moving said clamping jaws into and out of operative engagement with the shoes on said last members, and a manually operable clutch for initiating rotation of said shaft.

4. A device for smoothing the linings of shoes comprising a disc rotatable about a horizontal axis, last members exchangeably mounted on the periphery of said disc, heating elements within said last members, connections for the supply of current to said heating elements, clamping jaws engageable with both sides and the heel respectively, of shoes mounted on said last members, rotary eccentrics, rollers engageable with said eccentrics, levers carrying said rollers, other rollers also carried by said levers and double-armed jaw levers rockable into and out of smoothing position, said double-armed levers being operated by said second mentioned rollers.

JOHN HOZA.
